S. N. HALL.
PIPE WRENCH.
APPLICATION FILED, MAY 10, 1917.

1,333,251.

Patented Mar. 9, 1920.

INVENTOR.
Samuel N. Hall:

BY

Herbert
ATTORNEY.

UNITED STATES PATENT OFFICE.

SAMUEL N. HALL, OF MEMPHIS, TENNESSEE.

PIPE-WRENCH.

1,333,251.

Specification of Letters Patent.

Patented Mar. 9, 1920.

Application filed May 10, 1917. Serial No. 167,822.

To all whom it may concern:

Be it known that I, SAMUEL N. HALL, a citizen of the United States, and a resident of Memphis, in the county of Shelby, State 5 of Tennessee, have invented certain new and useful Improvements in Pipe-Wrenches, of which the following is a specification.

This invention relates to wrenches, and particularly to pipe wrenches of the chain 10 type, and especially the invention provides improvements in that type of a chain pipe wrench in which the pipe can be turned in either direction by the oppositely disposed teeth at one side of the longitudinal center 15 of the jaw plate with the same hitch of the chain about the pipe. A wrench of this general character is illustrated and described in U. S. Patent No. 889,246 dated June 2, 1908.

20 By the present invention a modification of this type of wrench is provided having a novel construction and mode of operation.

In the drawings—

25 Figure 1 is a side view of a wrench embodying my invention, with one of the jaw plates removed.

Fig. 2 is an edge view of a wrench in longitudinal section.

Fig. 3 is a view similar to Fig. 1, but with 30 the fittings jaw attachment.

Fig. 4 is an edge view of the fittings jaw.

Referring to the drawings, *a* denotes the handle, *b*, *b*, the jaw plates; *c*, *c*, the bolts by which the jaw plates are attached to the handle, *d* the chain anchored at one end on the bolt *c*; *e*, *e*, are lugs, as here shown on the handle, for engaging the ends of the chain pins *f*. The upper end of the handle is slotted to receive the chain, as at *g*, and a 40 bushing *h* holds the bifurcated ends of the handle so that they will not be sprung together by the outer holding bolt *c*. From the bottom of the slot the handle is grooved, as indicated at *i* so that the link by which 45 the chain is anchored to the bolt *c* will lie substantially below the rear teeth 10 and permit the chain to be swung far back when the rear teeth are being used.

Both edges of each jaw plate are provided 50 with a pair of oppositely acting teeth 5, 10, separated by a slight depression 11 to permit of the wrench being shifted to turn a pipe in either direction. When the parts are in the position shown in Fig. 1 with the rear 55 teeth engaged with the pipe, the pipe will be turned in a clockwise direction. When

the front teeth 5 are engaged with a pipe it will be turned in anti-clockwise direction.

It is important to remember that it is the set of oppositely disposed teeth at one side 60 of the longitudinal center of the jaw plates which coöperate to permit turning a pipe in either direction without disengaging the chain; this result being accomplished merely by pulling the wrench head across the pipe 65 when the direction of rotation is to be changed. It will be noted that the jaw plates are arranged symmetrically with respect to the handle; that is, the longitudinal axis of the jaw plates alines with the axis 70 of the handle. The jaw plates, symmetrical when considered with respect to their longitudinal centers, are not symmetrical when considered with respect to their transverse centers, since the rear end of the plates is 75 of greater width than the front end, carrying the rear set of teeth out away from the handle, where they can be utilized without the handle getting in the way of the work. This provides a well balanced wrench and 80 one in which the set of teeth on either side can be used without shifting the position of the jaw plates relative to the handle.

The pairs of teeth at each edge of the jaw slope away from one another at opposite 85 sides of the central depression, and are preferably slightly convex as shown. The jaw plates are spaced apart and in many cases the flange of a fitting would slip in between them so that the fitting could not be 90 operated by the wrench; in consequence, and especially in order to avoid the necessity of using a separate wrench, I have provided a fittings jaw which is intended, primarily, to operate on the flange of a fitting which 95 cannot be engaged by the regular jaw plates. 20 is the fittings jaw, positioned between the outer ends of the jaw plates, *b*, *b*, and held by pins 21 passing through the jaw plates and secured by cotter pins or nuts. This 100 fittings jaw projects outwardly beyond the forward teeth 5, and is designed to engage the flanges of pipe fittings. It is equipped with one or more engaging hooks 22 to take the pins *f* on the chain, thus obviating the 105 use of an unusually long chain, which would be necessary in order to hook the chain in the lugs *e*.

In accordance with the provisions of the patent statutes I have described the principle 110 of operation of my invention, together with the apparatus which I now consider to repre-

sent the best embodiment thereof; but I desire to have it understood that the apparatus shown is only illustrative, and that the invention can be carried out by other means.

5. I claim as my invention:—

1. A jaw plate provided at each edge with a pair of oppositely-acting teeth, one end of said jaw plate between the toothed portions on opposite sides thereof being of greater width than the other.

10. 2. A jaw plate provided with means at its rear end and on its longitudinal center for securing it to a handle, said jaw plate being of greater width at its rear end than 15 at its front end and projecting beyond the edges of the handle, and provided at each edge with a pair of oppositely-acting teeth.

20. 3. A jaw plate symmetrical as to its longitudinal axis and unsymmetrical as to its transverse axis, a depression in each edge at 25 a point between the ends of the jaw, and co-operating oppositely-acting teeth at the opposite sides of said depression.

30. 4. A handle, a pair of jaw plates secured to and projecting beyond the end of said handle and arranged so that the longitudinal axis of the jaw plates alines with the axis of the handle, a pair of oppositely-acting teeth on both edges of said jaw plates, the toothed rear edges of said plates being spaced from the edges of said handle, a chain having one end anchored at the end of the handle, and chain-engaging lugs on the sides of the handle near the end, said 35 chain being adapted to coöperate with either one of the pairs of teeth on the same side of the jaw plates to grip a pipe and turn it in either direction.

40. 5. A handle with a bifurcated end, a jaw plate at each side of the handle projecting beyond the bifurcated end and arranged with its longitudinal axis alined with the axis of the handle, a chain with one end secured to the handle back of the center of the 45 jaw plates, a bolt passing through said jaw plates and handle and on which the end of the chain is swiveled, and engaging hooks on the handle back of the center of the jaw plates for the other end of the chain, each 50 jaw plate being provided at each edge with a pair of oppositely alined teeth; the rear teeth of each jaw plate being at a greater distance from the longitudinal center of the jaw than the front teeth.

55. 6. A handle, toothed jaw plates secured to opposite sides of the handle and projecting beyond the end thereof, an auxiliary jaw positioned between the outer end of said jaw plates, means for supporting said auxiliary jaw from said jaw plates, said auxiliary jaw projecting laterally beyond the edges of said jaw plates and provided with engaging teeth, a chain connected at one end

with said handle, and means with which the opposite end of said chain may be 65 inter-engaged.

7. A handle, toothed jaw plates secured to opposite sides of the handle and projecting beyond the end thereof, an auxiliary jaw positioned between the outer end of said jaw plates, means for supporting said auxiliary jaw from said jaw plates, said auxiliary jaw projecting laterally beyond the edges of said jaw plates and provided with engaging teeth, a chain connected at one end with 70 said handle, and means on said auxiliary jaw with which the opposite end of said chain may be engaged.

8. A jaw plate symmetrical as to its longitudinal axis and unsymmetrical as to its 80 transverse axis and having at each edge a pair of oppositely acting pipe engaging surfaces.

9. A handle, a pair of jaw plates secured to said handle and projecting beyond the 85 end of the same and so arranged that the longitudinal axes of the jaw plates alines with the axis of the handle, a pair of oppositely acting teeth on both edges of said jaw plates, the toothed rear edges of said 90 plates being spaced from the edges of said handle, and a chain adapted to coöperate with either one of the pairs of teeth on the same side of the jaw plates to grip a pipe and turn it in either direction.

95. 10. A handle, a pair of jaw plates secured to the handle and projecting beyond the end of the same and each having at one edge a pair of oppositely acting pipe engaging surfaces located entirely to one side of the 100 longitudinal axis of the handle, the rear active pipe engaging surfaces of said plates being spaced a greater distance from the longitudinal axis of the handle than are the front pipe engaging surfaces, and a chain 105 adapted to coöperate with either the front or rear pipe engaging surfaces of said plates to grip a pipe and turn it in either direction.

11. A handle, a pair of jaw plates secured to and projecting beyond the end of said 110 handle and arranged so that the longitudinal axis of the jaw plates alines with the axis of the handle, a pair of oppositely acting teeth on one edge of each of said jaw plates and located entirely to one side of the longitudinal axis of said handle, the width of said jaw plates between the longitudinal axis of the handle and the rear toothed edges of the plates being greater than the width of the plates between the longitudinal axis of the handle and the front toothed edges of said plates, and a chain adapted to coöperate with either the front or rear pipe 115 engaging surfaces of said plates to grip a pipe and turn it in either direction.

120. SAMUEL N. HALL.
